CLAIM

We claim the ornamental design for a double walled metallic bowl, as shown and described.

DESCRIPTION

FIG. 1 is a top perspective view of one example of a design for a double walled metallic bowl;

FIG. 2 is a front elevational view thereof, the rear elevational view, left end elevational view and right end elevational view being the same as the front elevational view shown;

FIG. 3 is a top plan view thereof;

FIG. 4 is bottom plan view thereof; and,

FIG. 5 is a sectional view thereof taken along line 5—5 of FIG. 3.

The ornamental design which is claimed is shown in solid lines in the drawings.
